(57) **CLAIM**

The ornamental design for a table, as shown and described.

DESCRIPTION

FIG. 1 is a perspective view of a table, showing my new design;

FIG. 2 is a perspective view showing the table in a second environment;

FIG. 3 is a front elevational view;

FIG. 4 is a rear elevational view;

FIG. 5 is a left side elevational view;

FIG. 6 is a right side elevational view;

FIG. 7 is a top plan view;

FIG. 8 is a bottom plan view;

FIG. 9 is a perspective view showing the table in open condition;

FIG. 10 is a front elevational view in open condition;

FIG. 11 is a rear elevational view in open condition;

FIG. 12 is a left side elevational view in open condition;

FIG. 13 is a right side elevational view in open condition;

FIG. 14 is a top plan view in open condition;

FIG. 15 is a bottom plan view in open condition;

FIG. 16 is a bottom plan view in open condition and in the second environment;

FIG. 17 is a perspective view showing the table in a third environment;

FIG. 18 is a front elevational view showing the table in a third environment;

FIG. 19 is a rear elevational view showing the table in a third environment;

FIG. 20 is a left side elevational view showing the table in a third environment;

FIG. 21 is a right side elevational view showing the table in a third environment;

FIG. 22 is a top plan view showing the table in a third environment;

FIG. 23 is a bottom plan view showing the table in a third environment;

FIG. 24 is a perspective view showing the table in open condition in a third environment;

FIG. 25 is a front elevational view in open condition in a third environment;

FIG. 26 is a rear elevational view in open condition in a third environment;

FIG. 27 is a left side elevational view in open condition in a third environment;

FIG. 28 is a right side elevational view in open condition in a third environment;

FIG. 29 is a top plan view in open condition in a third environment; and,

FIG. 30 is a bottom plan view in open condition in a third environment.

The broken lines are for environmental purposes only and form no part of the claimed design.

1 Claim, 30 Drawing Sheets
